UNITED STATES PATENT OFFICE.

JAMES M. SWANZY, OF BILOXI, MISSISSIPPI.

MORTISE-LOCK.

1,162,664.

Specification of Letters Patent. Patented Nov. 30, 1915.

Application filed October 4, 1913, Serial No. 793,395. Renewed May 28, 1915. Serial No. 31,082.

To all whom it may concern:

Be it known that I, JAMES M. SWANZY, a citizen of the United States, residing at Biloxi, in the county of Harrison, State of Mississippi, have invented certain new and useful Improvements in Mortise-Locks; and I do hereby declare the following to be a full, clear, and exact description of the invention, such as will enable others skilled 10 in the art to which it appertains to make and use the same.

This invention relates to improvements in locks, and particularly to mortise locks.

The principal object of the invention is to 15 improve and simplify the construction of locks of this character.

Another object is to provide a novelly 20 constructed means for reticulating the latch bolt of a lock and means for limiting the outward movement of the said bolt.

Other objects and advantages will be apparent from the following description, when taken in connection with the accompanying 25 drawings.

In the drawings: Figure 1 is a side elevation 30 of my lock. Fig. 2 is a top plan view. Fig. 3 is a vertical longitudinal sectional view on the line 3—3 of Fig. 2. Fig. 4 is a vertical transverse sectional view on the line 4—4 of Fig. 3.

Referring particularly to the accompanying drawings, 10 represents the face plate of the lock to the rear side of which are secured the rearwardly extending cylinders 11 and

35 12, the former of which contains the latch bolt, while the latter contains the lock bolt. The latch bolt consists of an elongated member 13 which has formed transversely through the forward portion thereof the 40 elongated longitudinal slot 14. On the forward end of the member 13 is the beveled head of the bolt 15, this head extending through an aperture in the face plate 10. Extending transversely through the cylinder 11 and through the slot 14 is a rectangular lug 16 which receives the screw 16', from the opposite side of the cylinder, a coiled spring 17 being disposed within the slot, and bearing with one end against the lug,

and with its other end against the inner 50 face of the head 15. This lug is so arranged as to engage a transverse web 18 forming a part of the member 13 to limit the outward movement of the bolt. The rear portion of the member 13 is provided with a longitudinal slot 19 slightly larger than the slot 14, this part of the bolt receiving therethrough the roll back 20. Extending into the slot 19, and at the rear end thereof are the ribs 21, these ribs being so arranged as to be received 55 in the circumferential groove 22 formed in the roll back. Formed vertically through the webs of the latch bolt, above and below the slot 19 are the longitudinal slots 19', the rear end walls of which are 60 engaged by the projections 24 formed on the roll back. In the lower cylinder 12 is arranged the usual lock bolt 25.

In placing the roll back within the slot 19, the roll back is inserted in advance of 70 the ribs 21, rotated until the projections 24 engage in the upper and lower slots 19', and then moved backwardly into the slot until the rib is engaged in the groove of the roll back. The roll back is thus prevented from 75 movement transversely of the bolt. It will also be noted that by the provision of the lug 16, no strain is brought to bear on the roll back, by the forward pressure of the spring 17, thus producing a lock or latch 80 bolt which will more quickly and easily respond to the action of the roll back.

What is claimed is:

In a mortise lock, a face plate, a cylinder secured to the face plate extending rearwardly therefrom, a latch bolt slidably mounted within the cylinder, said latch bolt having longitudinal slots formed therein, inwardly extending ribs carried by the rear portions of the walls of the rear slot, a roll 90 back having a circumferential groove and disposed in the said slot, said roll back having vertical and depending lugs, said ribs engaging in the groove of the roll back and holding the same against transverse movement in the slot, said latch bolt being provided with vertical slots receiving the lugs 95 of the roll back, a dividing wall between the

slots, and a transverse lug secured to the cylinder and passing transversely through a slot, and a spring disposed within the forward slot and bearing against the lug in the forward portion of the bolt, said lug engaging with said dividing wall to limit the forward movement of the bolt.

In testimony whereof, I affix my signature, in the presence of two witnesses.

JAMES M. SWANZY.
